MOLD FILLING APPARATUS

William E. S. Strong, New York, N. Y., assignor
to John B. Pierce Foundation, New York, N. Y.,
a corporation of New York

Application January 29, 1940, Serial No. 316,220

2 Claims. (Cl. 25—1)

This invention relates to measuring and distributing apparatus, and particularly to measuring and distributing apparatus designed to operate upon a cementitious mixture.

In my United States Patent No. 2,193,847, issued March 19, 1940, and entitled Method of producing molded concrete products and apparatus therefor, there is disclosed a method of molding a concrete shell for use as a component element in a composite insulated structural unit, by subjecting a plastic cementitious mixture to combined jarring and compression within the confines of a mold box and forming cover. In this connection, it has been found very advantageous to deposit a predetermined quantity of the cementitious mix in the mold box in approximately the configuration of the desired molded product, prior to the application of the forming cover. The apparatus of the present invention is designed especially for this purpose, but may also find application in a great many other circumstances demanding similar functional characteristics.

A primary object of the invention, then, is to provide apparatus capable of depositing a predetermined quantity of a plastic cementitious mixture in a mold box, or other appropriate receiving receptacle, according to a predetermined configuration.

An object is to provide apparatus as above which is relatively simple in construction and operation, and which may be economically employed for the purpose.

A feature of the invention resides in an arrangement of measuring mechanism which discharges, almost instantly, a predetermined quantity of the ready mixed cementitious material over substantially the complete open area of a mold box or other receiving receptacle, in combination with an arrangement of baffles for diverting selected portions of the descending material to predetermined positions in the mold box.

The cementitious mixture operated upon must be of a suitable shape-retaining consistency. It must be sufficiently moist to be substantially free from danger of disturbance by air currents, but must not be so wet as to flow after deposit. Preferably the mixture is moist without being sufficiently so to adhere together in a plastic mass until after it has been subjected to molding pressure.

While the apparatus was developed primarily for use with cementitious mixtures, it may be employed to advantage with other materials and mixtures possessing similar characteristics.

Further features and objects of the invention will be apparent from the following detailed description and the accompanying drawings.

In the drawings:

5 Fig. 1 represents a side elevation, partly in vertical section, of a preferred embodiment of apparatus pursuant to the invention;

Fig. 2 represents an enlarged fragmentary portion taken on the line 2—2, Fig. 1;

10 Fig. 3 represents an enlarged fragmentary detail view, in side elevation, of that portion of the apparatus which includes the distributing baffles, and which is illustrated in vertical section in the lower part of Fig. 1;

15 Fig. 4 represents a front elevation, partly in vertical section, of the apparatus;

Fig. 5 represents a top plan view of the apparatus, the upper gates being open for the discharge of material from the hopper into the 20 measuring chamber;

Fig. 6 represents a horizontal section taken on the line 5—5, Fig. 4;

25 Fig. 7 represents a top plan view of the mold box immediately following a complete operation of the apparatus of Fig. 1; and

Fig. 8 represents a detail view in vertical section of one of the air cylinders of the apparatus, complete with compressed air supply and exhaust piping.

30 The preferred form of apparatus illustrated in the drawings comprises, in its essentials, a hopper 10, a measuring chamber 11, a distributing chute 12, and diversion baffles 13.

35 The material operated upon drops in successive quantities from the hopper 10 to the measuring chamber 11, from where it is released, practically as a unit, drops down through the distributing chute past the diversion baffles 13, and comes to rest as a deposit of predetermined configuration extending over substantially the entire length and breadth of the open mold box, or other receptacle, into which it falls.

The hopper 10 is preferably formed by a box-like structure having substantially vertical walls for preventing arching of the material therein. It may be of sheet steel construction with an upper section 14 secured to a lower main section 15 by means of an angle-iron joinder, as at 16.

40 45 50 The measuring chamber 11 is formed in the main section 15 by means of retractable gates, hereinafter described, and the upper portion of the distributing chute 12 is formed by the lower portion of main section 15. The distributing chute 12 is relatively long, or high, so that the

released material which falls freely therethrough under the influence of gravity will gain momentum for insuring proper distribution thereof by means of diversion baffles disposed at the lower end of the chute.

The diversion baffles 13 preferably include an upper set of baffles 13a and a lower set of baffles 13b. The individual baffles of the upper set 13a are secured in a box-like section 17, which is secured to the lower end of main section 15 by an angle-iron joinder, as at 18. The individual baffles of the lower set 13b are secured within a similar box-like section 19 which is secured to the lower end of section 17, as by the angle-iron joinder 20. The lower end section 19 is open, and forms the discharge end of distributing chute 12.

In the construction of the measuring chamber 11 it is important that provision be made for successive fillings thereof, rapidly and completely, from the hopper 10, and that provision be made for the discharge of the measured material therefrom, substantially as a unit, over substantially the complete horizontal sectional area of the distributing chute to insure proper distribution and diversion of the measured material as it is deposited in the mold box 21, or some other suitable receptacle.

It should be noted in this connection that it is structurally advantageous that the horizontal sectional areas of the measuring chamber 11, distributing chute 12, and open mold box 21 be made equal and uniform throughout.

Functioning as material discharge valves or controls, retractable gate mechanism has been found to give highly satisfactory results both as the dump-type bottom of the hopper 10 and, as such, the top of the measuring chamber 11, and as the dump-type bottom of the measuring chamber 11.

An upper set 22 of oppositely retractable individual gates 22-1 and 22-2 is provided intermediate the upper and lower ends of main section 15 to form the dump-type bottom of the hopper 10. The individual gates extend through and operate within suitable horizontal slots provided in opposite walls of the section.

A lower set 23 of oppositely retractable individual gates 23-1 and 23-2 is spaced apart below the set 22 a distance determining the depth of the measuring chamber 11, and forms the dump-type bottom thereof. The individual gates of the lower set likewise extend through and operate within suitable horizontal slots provided in opposite walls of the section.

It is essential that the lower gates 23-1 and 23-2 be made to retract from closed position to open position rapidly in order to obtain the desired character of discharge of the material into the distributing chute. It is desirable that all the gates move rapidly from closed to open positions and vice versa for insuring rapid sequential production of units.

For this purpose, compressed air has been adopted as the motivating medium. At opposite lateral sides of each of the individual gates of the sets 22 and 23 are secured air cylinders, see the air cylinders 24 of the set 22 of retractable gates and the air cylinders 25 of the set 23 of retractable gates, Fig. 5.

In attaching the air cylinders 24 to the respective gates 22-1 and 22-2 of the set 22, lateral supporting elements 26 receive the gates at their bottom edges, securement being accomplished by suitable means, such as screws, see

27, Fig. 2, and receive the air cylinders at their outer broad faces, securement being had by suitable means such as screws, see 28, Fig. 1. In attaching air cylinders 25 to the respective gates

5 23-1 and 23-2 of the set 23, similar lateral supporting elements 29 receive the gates at their top edges, and, as is the case with frame elements 26, receive the air cylinders at their outer broad faces.

10 The box-like sections, joined together as described, are supported in such manner that a mold box, or other suitable receiving receptacle, may be placed thereunder and removed during the operation of the apparatus. A structural steel frame-work may be employed to advantage for this purpose. As illustrated, corner posts, such as the structural steel channels 30, rise from suitable foundation means such as a concrete or other type floor, and are secured thereto, as

15 by means of the bolted angle plates 31. Frame cross members 32 extend between adjacent corner posts, and frame cross members 33 extend between cross members 32 intermediate the corner posts. Two opposite walls of box section 15 are secured in any suitable manner, as by riveting or spot welding, to the frame cross members 33, Fig. 4. Additional frame cross members 34 are secured to the remaining two opposite walls of box section 15, and have frame members 35 secured at and depending from their ends.

20 Against the outside face of each of these two opposite walls of box section 15 which are slotted to accommodate the sets of retractable gates, and along the margins of the slots thereof, are secured an upper rectangular reinforcing piece 36 and a lower rectangular reinforcing piece 37. The reinforcing pieces are provided with outwardly extending peripheral flanges 36a and 37a, respectively.

25 Against the outside face of each of these two opposite lateral sides of the box sections which coincide with the lateral edges of the retractable gates, are attached upper and lower supporting frame elements 38 and 39, respectively, whose ends extend considerably beyond the box sections and provide anchorage for structure hereinafter described. They are secured, adjacent their mid-portions, to portions of peripheral flanges 36a and 37a of the reinforcing pieces 36 and 37, respectively, and are secured, adjacent their ends, to the lower end portions of depending frame members 35. They are thus held firmly in place.

30 Each of the supporting frame elements 38 and 39 is formed with a longitudinal, hollow body section having a longitudinal groove formed on the outer face of its outside wall, see the grooves 38-1 and 39-1, which provides a double trackway, and, further, is provided with a longitudinal, surface trackway, see the trackways 38-2 and

35 39-2. The longitudinal, surface trackway 38-2 is formed along the upper marginal edge portion of the outer face of the outside wall of the hollow body section of supporting frame element 38, and the surface trackway 39-2 is formed along the lower marginal edge portion of the outer face of the outside wall of the hollow body section of supporting frame element 39.

40 A bracket end member 38a extends at preferably right angles from each end of supporting frame element 38, and a bracket end member 39a extends at preferably right angles from each end of supporting frame element 39. The outer extremity of each bracket end member is drilled to receive the free end of the rod of a piston, see the pistons 40 in the upper group and the

pistons 41 in the lower group, which is threaded and is secured to the bracket end member by nuts, see the nuts 42 in the upper group, and the nuts 43 in the lower group.

The pistons 40 fit into and cooperate with the cylinders 24, and the pistons 41 fit into and cooperate with the cylinders 25, the pistons, in both instances, remaining stationary and the cylinders reciprocating back and forth along the length of the piston rods.

As aforesaid, the frame elements 26 carry the cylinders 24 and the frame elements 29 carry the cylinders 25.

Journalized on stub shafts which extend from the inner broad faces of frame elements 26 are 15 rollers 44, a stub shaft and roller being placed at each end of each cylinder, see particularly Fig. 1, thus supporting the offset weight of the cylinders. The rollers 44 fit into the grooves 38-1 and run along the double-trackways there provided, longitudinally of the supporting frame elements 38, as the cylinders reciprocate. Since frame elements 26 reciprocate likewise, gates 22-1 and 22-2 will, also, likewise reciprocate. The rollers may roll easily along the trackways, 25 for the fit is not snug.

For better supporting the weight of the cylinders 24, trackway strips 45 are suspended from hangers 46 in spaced side-by-side alignment with the longitudinal surface trackways 38-2 of the 30 frame supporting elements 38. Each set of spaced trackways, thus provided form a double trackway similar to the double trackway 38-1.

Journalized on stub shafts which extend upwardly from the top edge faces of the frame elements 26 are rollers 47, a stub shaft and roller being placed to correspond with each end of each cylinder, see particularly Fig. 5. The rollers 47 are received by and run along the double trackways formed, as aforesaid, by the longitudinal surface trackways 38-2 and trackway strips 45.

For insuring absolute synchronism of motion of the two oppositely disposed cylinders 24 operative on each gate of the set of gates 23, rack and pinion correlating mechanism is provided. A rack 48 is secured along the tops of each set of lugs 49, upstanding from the tops of each cylinder 24. A slender connecting shaft 50 extends between two laterally oppositely disposed racks 48, for each of the individual gates 23-1 and 23-2, along the width of the gate. It is journalized adjacent its ends in journal boxes 51, and has secured at its ends pinions 52 which mesh with the racks 48. Thus, the movement of oppositely disposed cylinders 24 of each set will be correlated at all times by the connecting shaft 50.

Since the set 22 of retractable gates must operate rapidly and smoothly under the burden of a considerable weight of material in the hopper 10, see Fig. 1, additional structure is provided for insuring smooth operation of the gates without the likelihood of sticking, during the opening and closing operations, because of misalignment. Accordingly, tie rods 53 are secured between related extended ends of supporting frame elements 38, connecting such related extended ends of the supporting frame elements together, see particularly Fig. 5. Journalized in spaced relationship on each of the tie rods 53 are guide sheaves 54. Structural elements 55 are secured to the upper rear margins of the retractable gates 22-1 and 22-2, providing anchorage for rearwardly extending tail pieces 56, which are formed and placed to engage the sheaves 54 and to travel 75

thereagainst during the reciprocative movement of the gates.

Referring now to the mechanism associated with the lower set of gates journalized on stub shafts which extend from the inner broad faces of frame elements 29 are rollers 57, see Fig. 2, there being a stub shaft and a roller positioned to correspond with each end of each cylinder 25. The rollers 57 are received by and run along the double trackways provided by grooves 39-1 of the supporting frame elements 39. Journalized on stub shafts which extend downwardly from the bottom edge faces of the frame elements 29 are rollers 58, a stub shaft and a roller being placed to correspond with each end of each of the cylinders 25. The rollers 58 are received by and run against the longitudinal surface trackways 39-2 of supporting frame elements 39.

Since the weight of material supported by the set 23 of retractable gates is considerably less than is supported by the set 22 of retractable gates, the cylinders 25 may be smaller than the cylinders 24, and guide structure, corresponding to the sheaves 54 and tail pieces 56, is not needed.

For insuring synchronous movement between the cylinders 25 disposed at opposite lateral sides of the gates 23-1 and 23-2, and, thus, smooth uniform movement for the gates themselves, rack and pinion coordinating mechanism similar to that above described in connection with the upper group of cylinders 24, may be employed. A rack 59 is secured at the lower ends of each set of lugs 60, see especially Fig. 1, which depend from the bottoms of each of the cylinders 25. A slender connecting shaft 61 extends between two laterally oppositely disposed racks 59, for each of the individual gates 23-1 and 23-2, along the width of the gate. It is journalized adjacent its end in journal boxes 62 which are secured to supporting frame elements 39. Pinions 63 are secured to the ends of each slender shaft 61, and mesh with the oppositely disposed racks 59.

The upper and lower supporting frame elements 38 and 39, respectively, may be tied together by tie rods 64 for the sake of greater rigidity.

It is contemplated that the cylinders will be motivated by compressed air. In Fig. 6, where a cylinder 24 is arbitrarily selected as representative and illustrated in detail, pipe lines 65, for carrying compressed air to and exhausting it from the respective cylinders, connect with the cylinder at opposite ends thereof. The inflow and outflow of compressed air to and from the cylinder may be controlled by any type of well known valve mechanism (not illustrated). Since there is nothing novel in the arrangement of pipe lines for conducting compressed air to the cylinders, no showing thereof is made in the other figures of the drawings.

Secured to the slotted walls of box section 15, between the slots thereof, are reinforcing pieces 66, see particularly Fig. 1. The lower edge of each reinforcing piece 66 is so located with respect to the upper surface of its respective individual gate of the set 23 of retractable gates, as to act as a scraper, cleaning the upper surface of the gate during the outward movement thereof.

For the same cleaning purpose, the individual gates of the set 22 of retractable gates are positioned with their upper surfaces substantially contiguous to the upper defining edges of the slots through which they move, see especially Fig. 1.

In the operation of the apparatus as thus far

described, supply of compressed air to and the exhaustion of same from the respective cylinders 24 and 25 are controlled in such manner that when the upper gates 22-1 and 22-2 are open, the lower gates 23-1 and 23-2 are closed, thus filling the measuring chamber 11 with material from the hopper 10. Closure of upper gates 22-1 and 22-2 isolates the material in measuring chamber 11 from the mass of material in the hopper. When lower gates 23-1 and 23-2 are subsequently opened, the isolated predetermined quantity of material in measuring chamber 11 falls freely through distributing chute 12. As has been pointed out previously herein, the rapid opening of lower gates 23-1 and 23-2, as accomplished by the air cylinders 25, releases the predetermined quantity of material in measuring chamber 11 almost simultaneously, and allows it to fall, substantially as a unit, throughout the entire cross sectional area of the distributing chute 12 and down past the diversion baffles 13.

As aforesaid, the diversion baffles 13 comprise, in the illustrated embodiment, an upper set 13a, and a set 13b spaced apart downwardly therefrom and extending transversely thereacross.

Each of the baffles in both the upper and lower sets is preferably of elongated plate form, adjustable in width, and comprises parallel, overlapping plate sections 13-1 and 13-2 adjustably secured together, as, for instance, by bolts 13-3 extending through the usual type of elongated adjustment slot formed preferably in the plate against which the nut abuts, i. e., plate 13-1. The baffles are secured to shafts 13-4 which extend between opposite walls of the box sections 17 and 19, and are journaled therein.

For adjusting the positions of the individual baffles relative to one another, the shafts 13-4 extend through and beyond the walls of the box sections 17 and 19 and have mounted thereon bifurcated arms 67, see particularly Fig. 3. Slotted strips 68 are secured to the outer faces of side walls of box sections 17 and 19 in such manner as to receive the floating bolt and nut assemblies 69 and to enable them to cooperate with the bifurcated ends of arms 67 in locking the respective baffles in any desired position, within certain angular limits.

The setting of the baffles in any particular instance of use of the apparatus predetermines the ultimate placement of the predetermined mass of material falling through distributing chamber 12. The baffles divert the falling material into predetermined placement in the mold box 21, as can be clearly seen from Figs. 1 and 6.

It is advantageous that provision be made for rapid positioning and removal of the mold box under and from the discharge end of the distributing chute 12. A series of rollers 70 jour-

naled within suitable bracket supports 71 provides a roadway for easily accomplishing the above. The mold box may rest upon a supporting sheet 72 for transportation purposes if desired.

5 While a particular embodiment of apparatus is here specifically illustrated and described as representative of what might be constructed pursuant to the inventive concepts taught herein, it is intended that the generic scope of the invention 10 as set forth herein and in the claims that here follow, shall cover many other particular embodiments which may well occur to those skilled in the art.

I claim:

15 1. In combination, an enclosed substantially vertical chute having considerable height and an open bottom, retractable dump means disposed at the upper end of said chute, said dump means being formed of sections which meet at substantially the center of the horizontal cross-sectional area of said chute and are arranged to be retractable therefrom, thereby dumping substantially uniformly over the said cross-sectional area of the chute, a plurality of baffle plates pivotally mounted upon individual pivots, within said chute adjacent the lower end thereof for diverting certain portions of dumped material as said material falls through the chute, means for moving said plates about said pivots to vary the 20 angularity of the plates relative to each other, means for locking said plates in the desired position, means for depositing a layer of material substantially uniformly over said retractable dump means, and means for simultaneously and rapidly retracting, and for simultaneously and rapidly returning, the said sections of said retractable dump means.

2. In combination, an enclosed, substantially vertical chute having considerable height and an open bottom, a pair of substantially horizontally disposed, oppositely retractable plates, operable as dump gates, and disposed at the upper end of said chute, said pair of oppositely retractable plates being arranged to meet along a substantially rectilinear line which substantially bisects the horizontal cross-sectional area of said chute, a plurality of baffle plates mounted upon individual pivots for adjustably varying the angularity of the plates relative to one another, means for locking said plates in adjusted position, said plates being disposed within said chute adjacent the lower end thereof for diverting certain portions of dumped material as said material falls through the chute, means for depositing a layer of material substantially uniformly over said retractable plates, and means for simultaneously and rapidly retracting, and for simultaneously and rapidly returning, said retractable plates.

WILLIAM E. S. STRONG.
